UNITED STATES PATENT OFFICE.

MARCUS T. LOTHROP, OF CANTON, OHIO, ASSIGNOR TO THE TIMKEN ROLLER BEARING COMPANY, OF CANTON, OHIO, A CORPORATION OF OHIO.

PYROMETER-SWITCH.

1,399,134.

Specification of Letters Patent.

Patented Dec. 6, 1921.

Application filed October 6, 1919. Serial No. 328,675.

To all whom it may concern:

Be it known that I, MARCUS T. LOTHROP, a citizen of the United States, and a resident of the city of Canton, in the county of Stark 5 and State of Ohio, have invented a new and useful Improvement in Pyrometer-Switches, of which the following is a specification.

My invention relates to electric switches, especially to those adapted for connecting 10 any one of a series of thermo-couples or similar sources of electric energy to a meter. It has for its principal objects to minimize the resistance to the feeble current of the thermo-couple, to provide for the rapid 15 reading of the temperatures of various units with a single instrument, to simplify the construction of the switch and to obtain advantages hereinafter appearing. The invention consists in the parts and combinations of parts hereinafter described and claimed.

In the drawings, which form part of this specification, and wherein like numerals refer to like parts wherever they occur, 25 Figure 1 is a plan view of a switch embodying my invention as applied to a pyrometer system, and

Fig. 2 is a vertical section of the switch along the line 2—2 of Fig. 1, the thermo- 30 couples and meter being shown diagrammatically.

A housing 1 has a horizontal ledge 2 on which is a base plate 3 of some material which is a non-conductor of electricity. The 35 base plate has concentric annular channels or troughs 4 therein which are adapted to contain mercury. The base plate also has a plurality of pockets or depressions 5 arranged concentric with said channels and 40 adapted to contain mercury. The pockets are arranged in pairs, the pockets of each pair receiving electrical conductors 7. Said conductors 7 are connected to wires 6 leading to the opposite sides of a thermo-couple 45 or other source of electricity. The channels receive electrical conductors 9 which lead to the terminals of a meter.

A glass cover 8 with a hole in the center rests on the housing. A flange 9 at the top 50 of the housing receives the ends of the arms of a spider 10. The under sides of the end portions of the spider arms are recessed to accommodate the marginal portion of the glass cover. The housing has recesses in its 55 lower margin to receive the ends of the arms

of a second spider 11. The spiders at the top and bottom of the housing have bearings 12 for a vertical shaft 13. The shaft has a switch arm 14 thereon provided with contact members 15 adapted to dip into the mercury in said channels and depressions. 60

The shaft is hollow and has a plunger 16 in the lower end on which the shaft is free to move. The limits of the relative movement of the shaft and plunger are fixed by 65 the coöperation of a slot 17 in the plunger with a pin 18 which passes through said slot and which is fixed in the walls of the shaft. A plug 19 which is screwed into the end of the lower bearing constitutes the support for 70 the bottom of the vertical shaft. Preferably an antifriction bearing 20 is interposed between the plug and the end of the shaft. The upper end of the shaft is closed by a plug 21 which is screwed therein. A spring 75 22 is interposed between the plunger and the plug. The spring is arranged to raise the shaft high enough to raise the ends of the contact members out of the mercury.

The shaft is provided with manually operable means for raising, lowering and rotating it. Preferably, the shaft has a handle or knob 23 attached to its upper end. The knob has an annular flange 24 thereon which has notches around its periphery adapted 85 to engage pins 25 projecting from the arms of the spider. In order to rotate the shaft it is necessary to raise it far enough to clear the tops of the pins. The notches of the flange are numbered. One of the pins co- 90 operates with the numbers to indicate the location of the arm with reference to the depressions.

When the handle is in its lowermost position, one end of each contact member dips 95 into a pocket and the other end dips into one of the channels and a circuit is completed leading from the thermo-couple to a pocket of mercury, thence through one of the conducting members of the handle to 100 one of the channels of mercury, thence to the meter, from the meter back to the other channel, from the channel through the other conducting member of the handle to the second pocket of mercury and thence back to 105 the thermo-couple.

My invention is useful for many purposes, but I have used it chiefly in connection with furnaces used in heating steel articles to be hardened. Each furnace is provided with 110

a thermo-couple and each thermo-couple has its opposite sides connected to one of the pairs of pockets. When it is desired to measure the temperature of any thermo-couple, it is only necessary to raise the handle, turn it until the contact members are above the pockets connected to that thermo-couple and then depress the handle, so that the contact members will dip into the channels and the desired pockets, thus completing a circuit between the thermo-couple and the meter, so that the amount of electricity generated by the thermo-couple, and hence its temperature can be indicated by the meter. The meter may be graduated in units of heat, if desired, instead of units of electricity. The device is especially useful in measuring very weak currents as there is no danger of the contact points becoming pitted or dirty and thus weakening the current. Any foreign matter will float on top of the mercury. The device is compact and enables one meter to be used satisfactorily with a large number of thermo-couples.

25 I have described a preferred form of my invention as applied to a particular use, but the switch hereinbefore described has many other uses. It is especially useful wherever it is desired to connect at will one electrical device to any one of a plurality of such devices. It is obvious that changes may be made without departing from my invention and I do not wish to be limited to the precise construction shown.

35 What I claim is:

1. An electric switch comprising a housing having a horizontal ledge on the inner side thereof, a plate on said ledge having annular channels and depressions arranged concentrically and adapted to contain mercury, and a pivoted switch arm provided with contact members adapted to dip into said channels and depressions.

2. An electric switch comprising a housing having a horizontal ledge, a base on said ledge, said base having annular channels and depressions arranged concentrically and adapted to contain mercury, a spider supported on said housing, a glass cover for said housing having a hole in the center thereof, the under side of the marginal portions of said spider having recesses to receive said glass cover, and a rotatable and axially movable shaft concentric with said channels and depressions, said shaft being provided with a flange having notches around its periphery and pins on said spider in position to engage said notches, whereby said shaft can be rotated only after it has been raised far enough for the flange to clear said pins.

3. An electric switch comprising depressions and annular channels arranged concentrically and adapted to contain mercury, a rotatable and axially movable shaft, said shaft having a switch arm thereon provided

with contact members adapted to dip into said channels and depressions, and having a flange thereon having numbers around its periphery and an indicator for coöperating with the numerals on the flange to indicate the location of said switch arm with respect to said depressions.

4. An electric switch comprising a base having depressions and annular channels arranged concentrically and adapted to contain mercury and a rotatable and axially movable shaft, said shaft having a switch arm thereon provided with contact members adapted to dip into said channels and depressions.

5. An electric switch comprising a base having depressions and annular channels arranged concentrically and adapted to contain mercury and a switch arm having contact members adapted to dip into said channels and depressions, said switch arm being rotatable about an axis concentric with said depressions and channels and being movable axially with respect to said depressions and channels.

6. An electric switch comprising concentrically disposed contact members, a rotatable hollow shaft concentric with said contact members, a closure for the upper end of said shaft, a plunger in the lower end thereof, said shaft being slidable thereon, a switch arm supported by said shaft and having members adapted to contact with said first mentioned contact members, and a spring in said shaft between said plunger and closure, whereby the contact members on said switch arm are held normally out of engagement with said first mentioned contact members.

7. A pyrometer system comprising a meter, a plurality of thermo-couples and means for selectively electrically connecting the respective thermo-couples to said meter, said means comprising mercury containing troughs and pairs of pockets, the opposite sides of each of said thermo-couples being respectively electrically connected to the contents of the members of one of said pairs of pockets, and the contents of said troughs being electrically connected to opposite sides of said meter, and means for electrically connecting the contents of said pockets respectively to the contents of said troughs.

8. A pyrometer system comprising a meter, a plurality of thermo-couples, and means for selectively electrically connecting the respective thermo-couples to said meter, said means comprising a plate having mercury containing channels and depressions arranged concentrically and means for selectively electrically connecting said depressions with said channels respectively.

9. A pyrometer system comprising a plurality of thermo-couples, a meter, and means for selectively electrically connecting

said thermo-couples respectively to said meter, said means comprising depressions and channels adapted to contain mercury, and means for selectively electrically connecting any two of said depressions with said channels respectively. 5 and having contact members adapted to dip into said channels and depressions. 20

10. A pyrometer system comprising a meter, a plurality of thermo-couples, and means for selectively electrically connecting the respective thermo-couples to said meter, said means comprising mercury containing channels and depressions arranged concentrically and means for selectively electrically connecting said depressions with 15 said channels respectively, said means comprising a rotatable and axially movable shaft concentric with said channels and depressions and an arm projecting from said shaft 25

11. A pyrometer system comprising a plurality of thermo-couples, a meter, and means for electrically connecting any of said thermo-couples to said meter at will, said means comprising depressions and channels adapted to contain mercury and a switch for connecting any of said depressions with said channels, said switch comprising an arm movable above said depressions and channels and contact members on said arm 30 adapted to dip into said depressions and channels. 30

Signed at Canton, Ohio, this 29th day of September, 1919.

MARCUS T. LOTHROP.
